UNITED STATES PATENT OFFICE.

WILLIAM E. PINCKNEY, OF PORTLAND, OREGON.

DOUBLE-POUNDER WASHING MACHINE.

Application filed November 10, 1924. Serial No. 748,921.

This invention relates generally to the washing machine industry, and particularly to that class of washers which are especially adapted for use in the home.

5 The first object of my invention is to provide an exceedingly simple and efficient washing machine which will greatly facilitate the washing, rinsing and bluing of clothes.

10 The second object is to employ a special arrangement of vacuum cups, or pounders, wherein both operations of washing and rinsing can be carried on at the same time, or one operation can be carried on in two places 15 at one time, thereby permitting one lot of clothes to be rinsed while a successive lot is being washed, instead of causing the operator to wait between batches or to drag the washing operation over a long space of time, 20 during which a great deal of heat is lost from the water employed.

The third object is so to construct the machine that the mechanisms of both sections are opposed in a manner to hold the parts in 25 a perfect state of balance at all times, thereby greatly cutting down the current consumption.

30 The fourth object is to employ the minimum number of gears and parts in the construction of the machine and to use only such standard gears as are commonly found in the various lines of machinery, and to operate these gears in an oil bath.

The fifth object is to so construct the machine that it will readily lend itself to the cheap manufacture and assembly of parts.

The sixth object is to so arrange the companion parts that the wringer employed need not be swung or moved out of position.

40 I accomplish these results in the manner set forth in the following specification and illustrated in the accompanying drawings, in which:

Figure 1 is a side elevation of the entire machine of which Figure 2 is a front elevation. Figure 3 is a horizontal section taken along the line 3—3 in Figure 1. Figure 4 is a horizontal section taken along the line 4—4 in Figure 5. Figure 5 is a vertical section taken along the line 5—5 in Figure 4. Figure 6 is a vertical section taken along the line 6—6 in Figure 4.

50 Similar numbers of reference refer to the same parts throughout the several views.

55 Referring in detail to the drawings, I have illustrated a frame consisting of the

legs 10 and the cross ties 11, 12, 13 and 14. Casters 15 are placed under the legs 10.

Supported on the cross ties 12 are the water containers comprising the floor 16, 60 side walls 17 and dividing partitions 18. A wringer 19 is permanently secured over the partition 18, and covers 20 and 21 are removably placed over the separate compartments on opposite sides of the wringer 19. 65

On the cross ties 11 is mounted a housing comprising a bottom 22, side walls 23 and a cover 24. The housing itself is somewhat in the form of a cross whose opposite ends 25 and 26 are T shaped and whose remaining opposite ends 27 and 28 are L shaped. 70

In that portion of the housing between the ends 25 and 26 are placed the bearings 29 and 30 and also 31 and 32. A sleeve 33 journals in the bearings 30 and 31 and has 75 formed thereon a flange 34. A worm wheel 35 is secured on the sleeve 33 between the flange 34 and the bearing 30. The ends of the sleeve 33 are provided with jaws 36 and 37, each of which consists of one-half of 80 the sleeve ends. In each of the bearings 29 and 32 journals a hub of the cranks 38 or 39. The shaft 40 is secured to the crank 38 and journals in the sleeve 33.

A collar 41 is pinned to the shaft 40 and 85 a slideable clutch collar 42 is adapted to engage the jaw 36 of the sleeve 33. The shaft 43 journals in the sleeve 33 and in the hub of the crank 39. A collar 44 is pinned on the shaft 43 and wears against the bearing 90 32. A clutch collar 45 is slidably mounted on the shaft 43 and can engage the jaw 37 of the sleeve 33.

On each of the cranks 38 and 39 is placed a pin 46 which can move in the slot 47 in 95 the yoke 48 which guides on the rods 49, which, in turn, are mounted on the floor of the housing. A plunger 50 is secured to the upper end of each yoke 48 and passes upwardly through the floor 16 and the stuffing box 51, and has mounted on its upper end a cross arm 52 to which are attached the pounders or vacuum cups 53, which may be of any desired type, but preferably along the line indicated in my Patent Number 100 1,557,270. A hole 54 of sufficient size to form a free passage for the lubricant should be provided under the bearings 29 and 32.

In the cover 24 are mounted the hand levers 55 and 56 on the shafts 57. The shafts 57 are provided with clutch collar engaging arms 58 which engage the collars 42 and 45. 110

In order to give the necessary stiffness to the cover 24, ribs 59 and 60 are provided.

A motor 61 is mounted on the angle irons 62 and through the universal joint 62^A drives 5 a shaft 63, which passes through the stuffing box 64 on the plate 65 which is secured to the housing wall 23.

The shaft 63 passes into the elbow shaped end 28 of the housing and has secured thereon 10 a bevel pinion 65 which meshes with the bevel gear 66 on the motor driven shaft 67, which journals in the bearings 68 and 69. A collar 69^A is pinned on the shaft 67. A worm 70 on the shaft 67 meshes with the 15 worm wheel 35. A second worm 71 on the shaft 67 meshes with the worm wheel 72 on the wringer shaft 73 which transmits power to the wringer rolls through the gear box 74 in the customary manner.

20 The operation of my device is as follows: Clothes are placed in the water containing compartment and its control lever 55 or 56, as the case may be, is pushed over to cause its clutch to rotate its related crank, which, 25 in turn, will cause the pounders 53 to move upwardly and downwardly at an appropriate speed, assuming, of course, that the motor 61 is operating.

When it is desired to rinse this lot of 30 clothes, the covers 20 and 21 are lifted off and the clothes are wrung into the next compartment under the control of the lever 74^A, and more clothes are placed in the first compartment. Both sets of pounders may 35 now be employed, but only in a direction opposite to each other. Herein lies the secret of the low power consumption of this machine, since the load is made remarkably uniform by this arrangement and does not 40 cause frequent drops in motor speed, with correspondingly larger current consumption.

Rinsing water may be replaced by bluing water, or both sections can be employed for rinsing or washing or bluing as may be desired, thereby greatly cutting down the total 45 amount of time required by the operator to completely wash a lot of clothes, and also reducing the amount of heat required for the operation by reducing the amount of time during which heat can radiate from the 50 washing water. When wringing the clothes out to dry, the covers 20 or 21 are put in place to catch the clothes from the wringer instead of letting them fall into the next 55 compartment.

It will be observed that no matter how careless or inexperienced the operator may be that the pounders will always oppose each other, owing to the nature of the jaws 60 and 37.

I am aware that many forms of washing machines have been constructed in the past, I therefore do not claim such devices broadly but have directed my claims to a special 65 form of machine and a unique mechanism for operating same, as set forth in the following claims:

I claim:

1. A drive for washing machines having, in combination, a cross shaped housing, one 70 pair of opposite ends of said housing having L shaped ends and the other pair of opposite ends having T shaped ends; a crank in each of said T shaped ends; a split shaft supporting said cranks; a motor; a motor drive shaft extending between said L shaped ends; a worm on the middle of said motor drive shaft for driving said split shaft; and a wringer drive shaft journaling in one of said L shaped ends and receiving power from said driven shaft and transferring same to an overhead wringer. 75

2. A drive for double plunger washing machines having, in combination, a housing; a motor mounted alongside of said housing; a drive shaft projecting from the motor shaft into said housing; a motor driven shaft journaling in said housing and geared to said drive shaft; a worm on one end of said motor driven shaft; a wringer shaft journaling in said housing; a worm wheel on the lower end of said wringer shaft meshing with said worm; a second worm near the middle of said motor driven shaft; a split transverse shaft over said second 95 worm; a clutch on each portion of said split shaft, each clutch having a single jaw; a sleeve on the adjacent ends of said split shaft having a single jaw at each end thereof adapted to be engaged by either of said 100 clutches in a manner that the two ends of said split shaft will always have the same relation when driven by said sleeve; a worm wheel secured on said sleeve and meshing with said second worm; a crank on each end of said split shaft; a slotted yoke alongside of each crank; a guide for each yoke; and a plunger attached to each yoke. 105

WILLIAM E. PINCKNEY.
